(57) **CLAIM**

The ornamental design for a tire tread, as shown and described.

DESCRIPTION

FIG. 1 is a perspective view of a tire tread of the present application;

FIG. 2 is a side view (and the other side view is identical);

FIG. 3 is a front view thereof;

FIG. 4 is an enlarged partial perspective view thereof;

FIG. 5 is an enlarged partial side view thereof; and,

FIG. 6 is an enlarged partial front view thereof.

In the drawings, the broken lines depict portions of the tire that form no part of the claimed design. Likewise, the tire interior forms no part of the claim. Further, it is understood that the circumferential broken line closest to the elements shown in solid line represent boundaries of the claim. The tire tread is understood to repeat throughout the circumference of the tire.
